UNITED STATES PATENT OFFICE.

CHARLES J. PERKINS, OF MANITOU, COLORADO.

SILO-ROOF.

1,221,373.

Specification of Letters Patent.

Patented Apr. 3, 1917.

Application filed March 11, 1915. Serial No. 13,742.

To all whom it may concern:

Be it known that I, CHARLES J. PERKINS, a citizen of the United States, and resident of Manitou, in the county of El Paso and 5 State of Colorado, have invented a certain new and useful Silo-Roof, of which the following is a specification.

The object of my invention is to provide a silo roof of simple, durable and inexpensive construction.

A further object is to provide a silo roof preferably made in metal sections, so constructed and arranged as to be readily connected together to form a continuous circular roof.

Still a further object is to provide simple and durable means for properly supporting the sections of the roof on the upper end of a circular silo.

20 Still a further object is to provide such means so constructed and arranged as to permit the proper raising and removal of the roof sections.

Still a further object is to provide such 25 a means so constructed as to permit the roof sections to be tilted upwardly to vertical position for filling the silo to the top.

My invention consists in the construction, arrangement and combination of the 30 various parts of the device, whereby the objects contemplated are attained, as herein-after more fully set forth, pointed out in my claims, and illustrated in the accompanying drawings, in which:

35 Figure 1 shows a side elevation, partly in section, of the upper end of the silo and a partially completed roof.

Fig. 2 shows a side elevation, partly in section, of a portion of the roof.

40 Fig. 3 shows a top or plan view of two sections of the roof, one section being provided with a door opening.

Fig. 4 shows a sectional view taken on the line 4—4 of Fig. 2.

45 Fig. 5 shows a top or plan view of the annular plate, and

Fig. 6 shows a side elevation of one of the brackets adapted for use on a wood silo.

In the exemplification of my invention 50 illustrated in the accompanying drawings, I have used the reference numeral 10 to indicate the top of a circular silo, which may be made of any suitable material.

For supporting the parts of my roof in 55 position, I provide a plurality of brackets.

In Fig. 1 I have shown the brackets of a form adapted to be used with a cement or masonry silo, while in Fig. 6 I have shown a form of the brackets for use with a wood silo.

The form of the bracket shown in Fig. 1 comprises an upright member 11 adapted to be at the top of the silo against the outside thereof, to extend to a position above the upper end of the silo. The lower end of the member 11 is bent slightly outwardly at 12. Formed on the upper end of the member 11 is a downwardly bent portion 13, on the lower end of which is a portion bent substantially in the form of a cylinder. Above 60 the cylindrical portion 14, and extending upwardly therefrom, is a portion 15, which at its lower end is bent over and downwardly at 16. The portion 16 is provided at its lower end with a horizontal flange 17 adapted to rest on the silo wall.

Hoops 18 engage the members 11 and hold the brackets in place on a masonry wall.

Where the bracket is formed to be used on a wood silo, the bracket is made with the portion 11, at the upper end of which is a portion 11^a adapted to rest on the top of the silo. At the inner end of the member 11^a is an upwardly extending portion 11^b, formed on the upper end of which is a portion 13 similar to that already described. The form of the bracket used with a wood silo has the portions 15 similar to those of the bracket used for a masonry silo. On the upper end of the portion 15 is a downwardly 70 extending portion 19, adapted to engage the inside of the silo wall. The portions 11 and 19 of the form of bracket used on a wood silo are connected together by a bolt 20 extending through said portions and silo, as 75 shown in Fig. 6. On the inner end of the bolt 20 is a nut 21.

Every other bracket is so made that the portions 13 and 15 rest adjacent to each other. The alternate brackets are so made 80 that the portions 14 and 15 are spaced from each other, for a purpose which will be herein explained.

Where the form of brackets shown in Fig. 1 is used, four of the brackets are 85 provided with portions 22 extending downwardly from the portions 17 and with horizontal portions 23.

At the lower ends of the portions 22 where the form of bracket shown in Fig. 6 is used, 90

a number of said brackets, preferably four, are provided at the lower end of the member 19, with a horizontal member 23.

Above the central portion of the silo there is provided an annular plate 24, having near its periphery a plurality of holes 25, the purpose of which will be hereinafter explained, and having a central opening 26.

On the lower part of the annular plate 24 10 is a solid cylinder 27 of smaller diameter than the plate 24.

The rafters of my silo roof are indicated by the reference numeral 28, and are preferably four in number. Their lower ends 15 are suitably beveled at 29 and 30 to rest against the portions 22 and 23 or 19 and 23, as the case may be. Their upper ends are similarly beveled to rest against the under surface of the plate 24 and the periphery of 20 the cylinder 27.

It will be understood that the plate 24 and cylinder 27 may be held in position during the assembling of the roof, by means of a scaffold or any suitable support. The 25 rafters may be secured at their lower ends by bolts or otherwise, if desired, to the members 23.

The sections of my improved silo roof are composed of metal, and are tapered toward 30 their upper or inner ends as illustrated in Fig. 3. They are curved at their lower ends to conform to the general outline of the round silo, as shown in said figure. Said sections are indicated generally by the reference character 35 A, and comprise flat members having at one side edge the upwardly extending flange 31, and at the other side edge the upwardly extending flange 32, formed on the upper end of which is a downwardly extending spaced flange 33. The flanges 32 and 33 40 are so arranged as to form a cover for the flange 31 of the next adjacent member A.

Each of the members A is provided with a 45 central, longitudinal, upwardly extending rib or bead 34. One of the members A is provided with a door opening 35. All of the members A but one are made as above described. One of the members A is provided at each side edge with a downwardly extending flange 36, as shown in Fig. 2. The 50 reason for making the one section of special form will be hereinafter referred to.

The members A are provided on their 55 lower surfaces near their lower ends with transverse blocks 37 having transverse openings in them. At the lower ends of the members A are portions 38 designed to form eaves.

Rotatably mounted in each block or member 37, is a shaft 39 having on each end a crank 40. The ends of the cranks 40 are rotatably mounted in the portions 14 of the brackets.

In assembling the parts one crank 40 is 60 inserted into the opening 14 of the bracket which has the members 13 and 15 close to-

gether, and the other crank 40 is then slipped down between the members 13 and 15 in the portion 14 of the bracket which has the members 13 and 15 spaced from each other. It will be seen that by making the 70 alternate brackets with the members 13 and 15 spaced, the cranks may be readily and easily assembled or removed from the brackets.

In assembling the roof after the brackets 75 are installed and the plate 24 is located in position and the rafters 28 are installed, the sections A are properly mounted on the upper end of the silo wall by mounting the cranks 40 in the brackets. One section is 80 then swung downwardly and inwardly until it rests above the edge of the annular plate 24. The next adjacent section is then swung downwardly and inwardly from the position shown by the dotted lines in Fig. 1 to position with its upper edge resting on the plate 24, and with the member 31 of one section received between the members 32 and 33 of the next adjacent section. The reason for mounting the sections on cranks will now be 85 apparent. If the sections were simply hinged to the upper end of the silo and swung downwardly and inwardly, the members 31 would not properly enter the channels formed between the members 32 and 33. 90 It is necessary to first raise the section above the next adjacent section and then lower it directly downwardly upon the section already installed to cause the member 32 to properly enter into the channel referred to. 95

The specially formed section shown at the center of Fig. 2 may be the first one installed. The other sections are then installed in section around the silo. The specially formed section is necessary in order 105 to adapt the roof to the irregularities in the shape of the silo.

It is common knowledge that so-called "round" silos are rarely, if ever, perfectly round at the upper end, and it is desired to 110 have some possibility of adjustment in the sectional roof in order to take into account inevitable irregularities or variations from a true circle. By the use of the specially formed roof section, the other sections may 115 be assembled around the roof and the roof properly completed in spite of variations in the form of the upper end of the silo, on account of the fact that the two sections adjacent to the specially formed section may 120 slide thereon and overlap the specially formed section so far as it may be necessary to accomplish a proper assembling.

Mounted on the upper central portion of 125 the silo roof is a cap comprising a hollow conical member 41, having the central downwardly extending member 42, which is designed to be received in the opening 26 and extends downwardly through the plate 24 and the cylindrical member 27. The mem- 130

per 42 is provided with openings 43 to receive a bolt or pin for locking the cap 41 in position on the roof.

In the practical use of my improved silo roof, the parts are assembled in the manner hereinbefore described and the roof completed. When it is desired to fill the silo, one of the sections A adjacent to the specially formed section A, is raised upwardly 10 at its lower end to the position shown by the dotted lines in Fig. 1, and is then swung outwardly. This motion is permitted by the cranks 40 on the shafts 39. The upward movement of the sections is such as to permit 15 their ready separation.

The sections are preferably provided near their upper ends with blocks 44 in which are pivoted rods 45 having at their free ends the right-angled extensions 46. When the 20 sections A are raised to vertical position, as shown at the right hand side of Fig. 1, the rods 45 are adapted to be moved to horizontal position with the extension 46 received in one of the openings 25, whereby the 25 upright section A is held in such position. The sections may be thus raised to vertical position entirely around the silo.

A screen or the like 47 may be mounted just inside the roof sections after they are 30 thus raised, and the silo may be filled with ensilage which may extend considerably above the top of such silo and will be held by the screen or the like 47. It will be understood that the cap 41 must be removed 35 before the silo sections are raised.

After the ensilage has settled, the screen 47 is removed, the rods 45 are unhooked, and the roof sections are lowered to their 40 assembled positions. The cap is then placed in position and locked by any suitable means.

It will be understood that changes may be made in the construction and arrangement of the parts of my improved silo roof,

without departing from its essential features and purposes, and it is my intent to cover 45 by this application any such changes which may be included within the scope of my claims.

I claim as my invention:

1. The combination of a circular structure 50 with a conical roof therefor, comprised of substantially triangular sections arranged in succession around the structure, the alternate roof sections being arranged to overlap at their side edges the sections on each 55 side thereof, said roof sections being extended beyond the circular structure at their lower ends and being pivoted on crank arms, whereby the sections may be swung upwardly and outwardly from the circular 60 structure so that the lower outer ends of the sections do not interfere with each other when the sections are raised to substantially vertical position for filling the circular structure from the top. 65

2. In a device of the class described, the combination of a circular silo wall with a plurality of hanger brackets each comprising a horizontal portion adapted to rest on the top of the silo wall, bearing members, 70 downwardly extending members adapted to engage the silo wall on the inside and outside thereof, and a hoop encircling said silo wall and engaging the downwardly extending bracket member for supporting the silo 75 wall and holding the bracket member in position thereon, the downwardly extending portions of said brackets being provided with inwardly extending members adapted to receive and support rafters. 80

Des Moines, Iowa, February 16, 1915.
